UNITED STATES PATENT OFFICE.

CHARLES F. ROCKSTROH, OF BROOKLYN, NEW YORK, ASSIGNOR TO
ROCKSTROH MANUFACTURING COMPANY, OF BROOKLYN, NEW
YORK, A CORPORATION OF NEW JERSEY.

PRINTING-PLATE HOLDER.

No. 811,328.

Specification of Letters Patent.

Patented Jan. 30, 1906.

Original application filed October 28, 1903, Serial No. 178,885. Divided and this application filed December 21, 1903. Serial No. 186,143.

To all whom it may concern:

Be it known that I, CHARLES F. ROCKSTROH, a citizen of the United States, and a resident of Brooklyn, in the county of Kings 5 and State of New York, have invented certain new and useful Improvements in Printing-Plate Holders, of which the following is a specification.

This invention relates to an improved 10 holder for stereotype, electrotype, or other printing-plates by which any-sized plates can be securely held for printing, and as more fully described in a similar invention of mine for which Letters Patent of the United States 15 were granted to me on January 26, 1904, for an improvement in printing-plate holders, No. 750,395, and in my other application for Letters Patent of the United States for a similar invention, Serial No. 178,885, dated October 28, 1903, and to which reference is hereby made.

The invention consists of a printing-plate holder having parallel slots in its upper surface at right angles with its edges and spaced 25 apart corresponding to the "point system" of type measurement, and in providing therefor suitable plate-clamp devices and also detachable, solid, and adjustable expandable plate-spacers adapted to fit between and engage 30 with the plates and fill the spaces between the latter, and being provided with means by which they bind in the slots in the holder and are held in position thereon and also secure the plates thereto.

My object is to provide a plate-holder having means by which such plates can be quickly and securely attached in any position thereon and laterally adjusted and aligned with great accuracy and so the width 40 of the spaces between the plates can be regulated and the plates secured in any desired position to the holder.

This is a division of the application Serial No. 178,885, dated October 28, 1903, and relates more particularly to the plate-spacers as used with my improved holder and with the other accompanying devices referred to therein and as more particularly pointed out in the claims.

The nature and objects of this invention are more fully explained in the following

specification, taken in connection with the accompanying drawings, forming a part thereof, and in which similar letters refer to similar parts in the several views.

In the drawings, Figure 1 represents a top view of a plate-holder with several plates secured thereto by my improved clamp devices and showing the spacers in position between two pairs of the smaller-sized plates 55 thereon. Fig. 2 is a top or plan view of a full-sized section of a holder, showing plates thereon having grooved edges and which are held to the holder by the clamps and also held and separated from each other by the 60 solid and adjustable spacers. Fig. 3 is a vertical sectional view on the line *a b* in Fig. 2 and showing three expandible spacers in side elevation and end view of the upper portions of two other spacers and between the plates. 65 Figs 4 and 5, respectively, are side and top sectional enlarged views of the expandible spacers. Figs. 6 and 7 are perspective views of solid spacers with one tongue and two tongues, respectively. Fig. 8 is a vertical 70 sectional elevation of a part of a curved plate-holder; showing one of my improved plate-clamps and three of the spacers and with the plates curved as upon a printing-press cylinder.

In the drawings, A A' are sections of the plate-holder, having the vertical Y-shaped slots A² A³ twelve points or one pica wide and forty-eight points or four picas between centers opening in from the top A⁴ of the holder 80 and having side grooves A⁵ A⁶.

B B represent plates secured to the holder by the clamps C C, the edges B' B' of which are beveled and the lips C' C' shaped to fit down upon the edges of the plates. The 90 lower portion C² of each clamp C is threaded laterally to fit the screw D, having the pinion D' secured thereto (or made integral therewith) near the head D². The screw D has also a threaded connection with the tumbler E and is provided with a washer F and journal-block F' and all of such dimensions that the whole device can be dropped freely into the slots A² A³ or removable therefrom, as desired. A rack-bar with a handle or a 95 wrench or any other suitable tool that will mesh with pinions D' D' of the clamp-screws 100

D D will turn the screws when they are in the slots, thereby causing the tumblers to engage therein, and the plates can thus be secured to, adjusted on, or removed from the holder. The clamp C may have a swivel connection with the threaded portion C² when a plate is to be set at an angle, as shown by plate B² in Fig. 1. The clamp may be of any length and have two or more screws, as shown by C³ in Fig. 1. When a clamp is attached to the holder, the upper edges E' E' of the tumbler E register with the upper surfaces of the grooves A⁵ A⁶ of the slots A² A³ and fall into either of said side grooves, according as the screw D may be turned in adjusting the clamp against the plate. When the tumbler E is in such a position, the screw D and the clamp E cannot come out of the slot, while the lip C' of the clamp C will draw down the plate upon the holder and hold it firmly thereon. The washer F between the pinion D' and the head D² of the screw D is larger than the pinion and may be of any desired shape, takes the back thrust of the screw, provides a smooth seat for the pinion to work against, and keeps the pinion clear of the bottom of the slot. The journal-block F', in which the head of the screw D is loosely fitted, also supports the head D² in the slot, takes the lateral thrust of the rack-bar. When used with a curved plate-holder, the under surface of the clamp and the upper surface of the tumbler can be curved to bring their points of bearing against the bottom of the slot and the upper surface of the side groove to suit the change of position of the screw as it is rotated therein and as the clamp and tumbler move along the screw to and from its head and as seen in Fig. 8. The head of the screw and washer can have their external surfaces convex to allow the screw to swing up and down in the slot. The bottom of the clamp rests upon the bottom of the slot and supports the screw in that direction. The clamps are inserted into the slots where the latter intersect in the holder.

G represents a solid spacer having tongues G' G' and V-shaped to correspond with the Y shape of the slots in the holder and into which they loosely fit when so used, as seen in Figs. 3 and 8. These spacers may be of any desired length or thickness and may have only one tongue, as in Fig. 6, two in Fig. 7, or more. In Fig. 2 a spacer with two tongues is indicated, showing how the tongues register with the slots in the holder. These tongues G' each comprise a shank connected to the plate and adapted to extend down into the V-shaped grooves of the printing-plate holder and a part broadened to conform generally to the undercut V-shaped grooves and which broadened part provides shoulders for effecting the attachment or connection of the spacer to the plate-holder.

G³ G⁴ represent sections of an expandible spacer G², having their upper extremities G⁰ shaped so that together they form a dovetail in cross-section and which may be expanded by means of the wedge G⁵, having a rib G⁶ to fit in a corresponding groove G⁷ in the section G³ and having a limiting-pin G⁸, which moves in a corresponding groove G⁹ in the other section G⁴. A screw G¹⁰, threaded in the section G⁴ and passing through the other section G³, holds the two parts loosely together, and a spring G¹¹ between the head G¹² of the screw G¹⁰ and the adjacent section G³ provides a spring tension to hold the two sections together and against the wedge G⁵. A dowel-pin G¹³ in the lower extremities G¹⁴ G¹⁵ of the sections also keeps them together. The section G³ has a lateral projecting lug G¹⁶, which extends under a plate when on a holder, preventing the spacer from coming out even when at a point where two slots cross each other. This expandible spacer is shown in Fig. 4 and between and holding two plates B⁵ B⁶ and all being shown sectionally and enlarged. In Fig. 2 a number of expandible spacers G² G² are shown between and holding the plates on the holder. These plates B⁵ B⁶ have a half dovetail groove B⁶ on their edges B⁷ B⁷, as indicated in Figs. 3, 4, and 8, and by dotted lines in Figs. 1 and 2, to correspond with the shape of the spacers. The wedge G⁵ of the expandible spacer G² has a hole G¹⁷ near its large end G¹⁸ and into which a tool may be inserted and by means of which the wedge G⁵ may be moved between the sections in regulating the adjustment of the plate. The expandible spacer acts as a clamp in holding the plate to the holder and also as a spacer in regulating the width of the space between the plates. If the sides of the expandible spacer are made flat, as indicated by the dotted lines in Fig. 4, it acts only as an adjustable spacer between the plates. It can also be made with one of its sections clamp-shaped and the other flat.

The solid form G of spacer shown separately in Figs. 6, 7 and in position in Figs. 1 and 2 can be used with the expandible spacer G², or either form can be used with the clamp devices.

In Fig. 8 the block A' is shown curved to fit upon the surface of the periphery H of the cylinder H' of a printing-press, a portion of which is shown in section with a portion of the holder and with two curved plates mounted thereon. In this view two of the expandible spacers curved to correspond with the curvature of the plates and holder are shown, and an end view of an expandible spacer is shown between the two plates. A clamp is also shown and holding one of the plates to the holder by its outer (right-hand) edge. These devices are like the other simi-

lar devices, except in their curved surfaces, where the principle of curvature necessitates modification of shape. The spacers have only such portions thereof curved as are above the surface of the holder. The clamp requires only the external surfaces of the pinion-head and washer of the screw and the upper surface of the tumbler and lower surface of the clamp of a convex curvature, as indicated in this figure, (Fig. 8.)

The spacer devices can all be used upon a curved plate-holder by modifying their construction to suit this principle of curvature.

The plates may have their edges with a plain bevel, as seen in Fig. 1, or with an undercut bevel or groove, as seen in Figs. 1, 2, 3, 4, and 8, and the clamps and spacers can be used equally well with both forms of plate.

The operation of my improved holder will now be explained. When a plate is to be mounted upon the holder, the clamps are placed in the slots all complete, as seen in Figs. 1, 2, 3, and 8, and in an approximately proper distance apart to take the plates between the clamps. The plate is then placed upon the holder between the clamps, and the latter are screwed firmly against the edges of the plate by turning their respective pinions by means of a rack-bar or wrench or any other suitable tool over the pinion or pinions of the screw or screws to be thus adjusted. A printer can thus close or open the clamps with reference to the plate very quickly. When the "margin" between the plates is narrow, by making the screws with right-hand and left-hand threads for opposite plates the release of a number of plates can be effected very rapidly with a few quick movements of a hand rack-bar. (A well-

known tool in the trade, so needing no description here.) When the space between the plates is too small to admit of the use of the clamps, the spacers can then be used instead, and a very close adjustment of the plates can be obtained thereby and as indicated by the arrangement of the plates, as seen in Figs. 2, 3, 4, and 8. Both forms of the spacer can be used together also and as seen between the two pairs of plates in the lower left-hand corner of Fig. 1 and a comparatively wide range of adjustment obtained by their use in this way. The solid spacers can also have their upper portions leveled to match the bevel of the expandible spacer when both forms are used together and which can be understood without illustration. The slots being at right angles with the edges of the holder enables the printer to set the plates in accurate and correct alignment thereon and while in position upon the bed of a printing-press and which is of great advantage. The slots are arranged in the holder so that they register corresponding to what is known as the "point system" in the

printing trade, and the advantages of which 65 in adjusting the plates upon a holder are correspondingly very great. The point system is a standard of measurement of the bodies of type, one point being equal to .0138 of an inch, nonpareil type measuring six points, 70 pica measuring twelve points, and so on. Pica type is the standard unit of measurement in the printing trade for the thickness and length of leads, rules, &c.—as, for instance, a six-to-pica lead, a page twenty-four 75 picas wide, and the like. The slots in the holder are one pica in width and four picas (or forty-eight points) from center to center, thus leaving the intervening squares three picas or about a half-inch in size. If a plate 80 is to be set on the holder at an oblique angle with the edges of the holder, as shown at B² in Fig. 1, the swivel form of construction of the clamp will allow the clamp to adjust itself against the edge of the plate accordingly and 85 as several are shown as securing the plate B² in the holder in Fig. 1.

The advantages of my improved holder are that it can be made of any dimensions or shape to suit the size or position in which the plate or plates are to be mounted thereon and that it can be readily moved and cleaned, that the construction of the clamps admits of their being adjusted to any position on the holder by simply inserting them into the slots 90 where they intersect from the top of the holder and with their automatic tumbler-locking section gives them fine, accurate, and positive lateral adjustment, and that the solid and expandible spacers can likewise be 100 accurately adjusted in their proper and desired position in the slots and from the top of the holder and the plates held thereto and spaced apart thereby, the arrangement of the slots at right angles with the edges of the 105 holder and with each other and upon the point system of measurement, which facilitates the adjustment of the plate or plates thereon while being upon the bed of a printing-press. When the plates are to be placed 110 so closely together that the spaces between them are too small to admit of the use of the clamp devices thereat, the spacers are used as shown in Figs. 1, 2, 3, and 8, and so the plates can be set at any close proximity together. As these spacers can be of any desired thickness or length and either solid or 115 expandible and of plain or clamp shaped construction and can be used with or without the regular clamp devices, as already described, 120 it can be seen that plates can be thereby spaced or clamped as closely together in printing therefrom as may be desired and a 125 comparatively wide range of adjustment obtained as well. The wedge means of adjustment of the width of the expandible spacer being entirely above the surface of the plateholder admits of the bringing together, if

necessary, of the sections of the spacer, thus minimizing the width between two plates, which is often very necessary, and which could not be accomplished if the sections of the spacer were expanded by means of a screw, cam, or other mechanical equivalent for the wedge under other conditions and which would be covered up by the sections of the spacer if located in the slot of the holder (as would necessarily have to be the case) if those equivalents were used as means of expanding the sections.

In the printing or lithographing of labels or like work these clamps and spacers are especially adaptable, as close margins and accurate register and adjustment of the plates are absolutely necessary in this class of work and to meet the requirements of which these improved devices have been particularly de- signed.

When the plates are to be printed from a curved support, such as the cylinder of a printing-press, the holder can have its surfaces and slots curved and the clamp mechanism and the spacer devices can be correspondingly curved and shaped to fit such modification of construction, as indicated in Fig. 8. The principle of curvature as applied to the holder can be extended to admit of the holder forming the entire outer portion of the cylinder of a printing-press or to comprise sections of the same.

Having thus described my invention, what I claim, and desire to secure by Letters Patent, is—

1. The expandible spacer, G^2 , for a printing-plate holder having slots therein, having one or more tongues fitted loosely in the slots in the holder and consisting of the sections, G^3 , G^4 , which are loosely connected together, and the wedge, G^5 , fitted between them so as to give a lateral expansion of dimensions to the spacer, and all combined, as specified.

2. The expandible spacer, G^2 , for a printing-plate holder having slots therein, consisting of the section, G^3 , having its upper extremity, G^6 , half dovetail in shape to fit in the clamp-groove, B^6 , of the plate, B^5 , and having a lateral projection, G^{16} , and a dowel-pin, G^3 , in its lower extremity, G^{14} , which is dowelled in the lower extremity, G^{15} , of the corresponding section, G^4 , of the device, which is also shaped at its upper extremity G^6 dovetail in section to fit in a corresponding groove, B^6 , of the plate, B^5 , and the wedge, G^5 , fitted between the two sections, and provided with the rib, G^8 , the limiting-pin, G^9 , and the hole, G^{17} , and the screw, G^{18} , fitted to the section, G^4 , and loosely fitted through the section, G^3 , and the tension-spring, G^{11} , between the section, G^3 , and the screw-head, G^{12} , and all combined, as specified.

3. The expandible spacer, G^2 , for a printing-plate holder having slots therein, consist-

ing of the sections, G^3 , G^4 , and the wedge, G^5 , as a means for changing its lateral dimensions while in position upon the holder, and all combined, as specified.

4. In a printing-plate holder having undercut V-shaped grooves therein, a spacer comprising a plate adapted to set between printing-plates secured to the surface of the holder and having tongues each with a shank extending down into and a part broadened to conform generally to said undercut V-shaped grooves providing shoulders for attachment of the spacer to the plate-holder.

5. In a curved printing-plate holder having undercut V-shaped grooves therein, a spacer comprising a curved plate adapted to set between curved printing-plates secured to the curved surface of the holder, and having tongues each with a shank extending down into, and a part broadened to conform generally to said undercut V-shaped grooves providing shoulders for attachment of the spacer to the plate-holder.

6. An expandible sectional spacer, for a curved printing-plate holder, provided with the tongue, G' , as a means for its attachment to the holder and its upper portion being provided with the wedge, G^5 , as a means for changing its thickness laterally, as specified.

7. The curved expandible spacer, G^2 , for a curved printing-plate holder, consisting of the sections, G^3 , G^4 , having the tongue, G' , as a means for its attachment in the slots therein, and the wedge, G^5 , for changing the lateral dimension of the spacer, and all combined, as specified.

8. In a printing-plate holder, an expandible spacer consisting of a pair of similar yieldingly-connected members constructed for engagement with the slots of the plate-holder and for opposite contact with plates to be held to the plate-holder, and a wedge fitted between parts of the spacer to give lateral expansion to the dimensions thereof.

9. The combination with a printing-plate holder having series of undercut slots, of an expandible spacer, consisting of a pair of similar yieldingly-connected members having parts adapted to pass into said slots and interlock therewith and parts adapted to lie above the surface of the printing-plate holder and to engage edge grooves of said printing-plates, the inner opposite faces of the latter parts being grooved and a wedge fitting between said latter parts and movable along said grooves to give lateral expansion to the dimensions thereof.

10. The combination with a printing-plate holder having series of undercut V-shaped slots, of an expandible spacer, consisting of a pair of similar yieldingly-connected members having tongues adapted to pass down into and broadened to conform generally to said slots and interlock therewith, and parts

adapted to lie above the surface of the printing-plate holder and to engage edge grooves of said printing-plates, the inner opposite faces of the latter parts being grooved and a wedge fitting between said latter parts and 5 movable along said grooves to give lateral expansion to the dimensions thereof.

Signed at New York, in the county of New York and State of New York, this 18th day of December, A. D. 1903.
